RESTRICTOR VALVE FOR A SERVOMOTOR CIRCUIT

Walter Ernst, Dayton, Ohio, assignor to The Thompson Grinder Company, Springfield, Ohio, a corporation of Ohio

Original application April 3, 1951, Serial No. 219,039. Divided and this application April 12, 1952, Serial No. 282,013

9 Claims. (Cl. 60—52)

1

This invention relates to hydraulic servo-motor systems and to methods of operation thereof, and particularly to an automatic restrictor valve adapted for being placed in such a servo-motor circuit.

This application is a division of my co-pending application, Serial No. 219,039, filed April 3, 1951, and assigned to the same assignee as the instant application.

In servo-motor systems of any type, it is necessary to arrive at a compromise between sensitivity and stability. This comes about because in an extremely sensitive servo-motor system the part that is moved at the output side of the system will have a tendency to overrun the part that is moved at the input side. With a system, on the other hand, that is extremely stable this tendency is eliminated but, at the same time, a great deal of accuracy of adjustment is lost.

Having the foregoing in mind, the present invention has as its primary object the provision of a servo-motor system, particularly a hydraulic system, which is extremely stable in operation but which, at the same time, is also extremely sensitive.

A particular object of this invention is the provision of an automatic restrictor valve for a hydraulic servo-motor system, which will operate to permit rapid movement of both the input and output members of the system, but which will prevent overrunning of the input member by the output member.

A still further object is the provision of a method of operating a hydraulic servo-motor system by which increased sensitivity and stability are obtained.

These and other objects and advantages become more apparent on reference to the following specification taken in connection with the accompanying drawing:

Figure 1 is a more or less diagrammatic plan view of a hydraulic servo-motor system according to my invention associated with a load to be moved thereby.

Figure 2 is a diagrammatic representation of the elements of the servo-motor system of Figure 1; and,

Figure 3 is a sectional view indicated by line 3—3 on Figure 1, showing the automatic restrictor valve of this invention.

2

Referring to the drawing somewhat more in detail, the arrangement illustrated in Figure 1 comprises a bed or frame 10 on which is slidably mounted a table 12. The bed and table may represent, for example, a grinding machine wherein the table 12 is the part that supports the work piece to be operated.

Mounted in bed 10 is a hydraulic cylinder 14 in which is reciprocal a piston 16 having the rod portions 18 and 20 extending opposite ways therefrom. Rod 18 is connected for reciprocating table 12 on bed 10.

For supplying pressure fluid to cylinder 14 on the opposite sides of piston 16 there is provided a pump 22 connected for drawing fluid from a reservoir 24 and discharging the said fluid to a pressure conduit 26.

Pressure conduit 26 leads to the inlet port of a servo valve, generally indicated at 28, and which is more fully disclosed and described in my co-pending application referred to above.

The servo valve 28 also comprises an exhaust line 30 leading back to reservoir 24 and the service conduit 32 leading to the left end of cylinder 14, and service conduit 34 leading to the inlet port of a valve comprising a body 36 and having an outlet port connected by conduit 38 with the right end of cylinder 14.

The servo valve 28 is of the type having a valve member for controlling flow from conduit 26 to the service conduits 32 and 34 and also for controlling the flow from the service conduits to the exhaust conduit 30. A hand wheel 40 is provided for rotating the valve member for reversibly connecting the service conduits with the pressure and exhaust conduits.

The servo valve is of the follow-up type and comprises a sleeve connected with pinion 42 that is engaged by rack 44 connected to reciprocate with table 12. The arrangement is such that a predetermined adjustment of the valve member of the servo valve will be accompanied for a corresponding amount of movement of table 12.

In the type of machine tools with which a servo-motor mechanism according to my invention is most useful, the table 12 and the work members mounted thereon represents a substantial mass and for this reason once set in motion, has considerable inertia and will, therefore, have a tendency to overrun the position

3

in which it is to be halted if it approaches the said position at a high speed.

At the same time, it is many times desirable to adjust the table 12 at a high rate of speed and if the servomotor system is normally so adjusted as to prevent the overrun of the table, it will be so sluggish that a rapid adjustment of the valve member of the servo valve will permit the servo valve member to overrun the table, whereby control over the table is entirely lost.

In order to provide for rapid adjustment of table 12 and, at the same time, to prevent the overrunning thereof, I provide the valve having a valve body 36 into which conduit 34 leads from the servo valve and from which conduit 38 leads to the right end of cylinder 14.

In Figure 3 it will be noted that valve body 36 has a valve bore 46 therein which comprises a central chamber 48 and the interconnected end chamber 50. A valve member 52 is reciprocal in bore 46 and includes the reduced diameter center part 54 and the outwardly tapering portions 56 that connect central part 54 with the end spools 58 that fit closely in bore 46.

The ends of the valve member comprise stems 60 extending into the pilot cylinders 62 so that pressure fluid conducted to the pilot cylinders will act on the ends of the stems.

Within each pilot cylinder there is a spring 64 bearing between the outer closed end of the pertaining cylinder and a washer 66 that rests on a shoulder formed on the stem.

The springs 64 thus serve as centering springs for normally retaining the valve member in its centered position.

Each pilot cylinder has an adjustable abutment screw 68 for stopping the valve member at a predetermined shifted position.

The central chamber 48 in the valve body communicates with interconnected chambers 50 by means of a bore 70 adapted for being variably restricted by adjustable needle valve 72.

Connected with each of the pilot cylinders is a pilot conduit 74 and the pilot conduits are connected with the service conduits 32 and 34 at a position therealong close to the point where the service conduits connect with the servo valve 28.

Reference to Figure 3 will serve to reveal that whenever fluid pressure in a sufficient amount is delivered to either one of the pilot cylinders 62 the valve member 52 will be shifted from its centered position, thus establishing a by-pass around bore 70 and thus reducing the restriction offered to fluid flow from conduit 38 to conduit 34 or vice versa.

The illustration in Figure 2 diagrammatically shows the manner in which the servomotor system; according to the present invention, operates. In this view the conduits correspond to those in Figures 1 and 3 and the servo valve 28 is represented by the bridge arrangement of resistors.

In Figure 2 resistor R1 represents the passage in valve 28 between conduit 26 and conduit 34; R2 represents the passage between conduits 26 and conduit 32; R3 represents the passage between conduit 34 and exhaust conduit 30; and R4 represents the passage between conduit 32 and exhaust conduit 30.

When valve 28 is adjusted one of the resistors R2 and R4 will be decreased and the other simultaneously increased and the one of the resistors, R3 or R4 directly opposite the increased resistor will be also increased and the other thereof decreased. This adjustment effects a pressure

4

change between conduits 32 and 34 which brings about movement of piston 16 and its connected parts until the original condition of balance within valve 28 is restored.

In normal operation, valve member 52 of the automatic restrictor valve remains in its centered position and creates a predetermined restriction to fluid flow to or from cylinder 14 in either direction of movement of piston 16 thereby damping movements of piston 16 and its connected parts and thus preventing overrunning of the said piston when adjustment of the valve is halted.

However, should it be desired to bring about rapid movement of piston 16 and valve 28 is adjusted rapidly, then a high pressure differential is set up between conduits 32 and 34 and this pressure differential, via the pilot conduits 74, is impressed on valve member 52 thereby bringing about shifting of the valve member in one direction or the other into its by-passing position and thereby reducing the restriction offered to fluid flow to or from cylinder 14, thus permitting piston 16 and its connected parts to follow even the most rapid adjusting movements of the servo valve.

When the piston 16 and its connected parts approach the point where it is desired for them to come to rest movement of the servo valve will naturally be toward a position in which the piston will be slowed down. Movement of the servo valve to such a position will reduce the pressure differential between conduits 32 and 34, thus permitting valve member 52 to return to its centered position where it again creates a restriction in the fluid flow to or from cylinder 14, thereby damping movements of piston 16 and its connected parts, whereby they do not overrun when adjustment of the servo valve is finally halted.

In the foregoing it is seen by the use of the automatic restrictor valve, the servo-motor system can be made highly sensitive and quick acting so that the member moved at the output side of the system will respond immediately to the most minute adjustments of the servo valve and also follow the most rapid movements of the servo valve but, at the same time, the said parts will not overrun the servo valve at any time. Control over the parts moved at the output end of the servomotor is thus positive and continuous under all circumstances.

It will be understood that this invention is susceptible to modification in order to adapt it to different usages and conditions, and, accordingly, it is desired to comprehend such modifications within this invention as may fall within the scope of the appended claims.

I claim:

1. In a restrictor valve; a valve body, a pair of ports in said valve body, parallel flow passages in said valve body connecting said ports, a restrictor in one of said passages, a valve member normally closing the other of said passages when in a centered position and having opposite end positions where the said other passage is established, said valve member having stem portions extending out opposite ends of the valve body, spring means acting on said stem portions normally urging said valve toward its center position, a pilot cylinder enclosing each stem portion, and means for conveying pressure fluid to said pilot cylinders for acting on said stem portions, for moving said valve member toward one or the other of its end positions, said pilot cylinders including abutment means for prede-

terminating the opposite end positions of said valve member, and each end of said valve member comprising a tapered portion that is disposed in the mouth of said other passage when said valve member is shifted toward the pertaining end position of the valve member whereby adjustment of said abutment means will determine the degree of restriction of said other passage means when the valve member is shifted.

2. In a restrictor valve; a valve body having a pair of ports, a central cavity in the body communicating with one of the ports, interconnected end cavities in the valve body in communication with the other port, a valve bore in the body leading from the end cavities to the central cavity, another bore in the body interconnecting the central cavity with the end cavities, a restrictor in said other bore, a valve member mounted in the said valve bore, said valve member comprising spaced spool portions in the said valve bore, and a central reduced diameter portion in said central cavity and tapering portions connecting the central portion with the said spool portions, said valve member comprising stems extending toward opposite ends of the valve body, pilot cylinders receiving said stems, springs in the cylinders acting on the stems normally urging the valve member to a centered position where it closes said valve bore and prevents communication between said central cavity and end cavities, and means for conducting pressure fluid to said cylinders for moving the valve member from its centered position to open the valve bore at one end or the other thereof to establish communication between said central cavity and said end cavities.

3. In a restrictor valve, a valve body having a valve bore, a valve member reciprocably mounted in said bore, chambers in said valve body at each end thereof intersecting said bore and hydraulically interconnected, said valve member having a center position where communication between said bore and chambers is interrupted, and having opposite end positions where said communication is established, means normally centering said valve member, fluid operable means for moving said valve member into either of its end positions, and a restricted channel continuously connecting said bore and chambers.

4. In a restrictor valve, a valve body having a valve bore, chambers adjacent the ends of said body intersecting said bore, said chambers being hydraulically interconnected, a first port in said body opening into said bore and a second port in said body opening into said chambers, means affording continuous restricted communication between said bore and chambers, a valve member in said bore having a center position where the ends of said bore are closed and having opposite end positions where one or the other of the ends of said bore opens into the adjacent of said chambers, pilot cylinders on the ends of said body, said valve member having end parts extending into said cylinders, spring means in said pilot cylinders acting on the said end parts for normally centering said valve member, and means for conveying fluid pressure to said pilot cylinders for moving said valve member into its end positions against the influence of said springs.

5. In a restrictor valve, a valve body having a valve bore, chambers adjacent the ends of said body intersecting said bore, said chambers being hydraulically interconnected, a first port in said body opening into said bore and a second port in said body opening into said chambers, means

affording continuous restricted communication between said bore and chambers, a valve member in said bore having a center position where the ends of said bore are closed and having opposite end positions where one or the other of the ends of said bore opens into the adjacent of said chambers, pilot cylinders on the ends of said body, said valve member having end parts extending into said cylinders, spring means in said pilot cylinders acting on the said end parts for normally centering said valve member, and means for conveying fluid pressure to said pilot cylinders for moving said valve member into its end positions against the influence of said springs, there being adjustable abutment members in said cylinders for predetermining the end positions of said valve member.

6. In a restrictor valve, a valve body having a valve bore, chambers adjacent the ends of said body intersecting said bore, said chambers being hydraulically interconnected, a first port in said body opening into said bore and a second port in said body opening into said chambers, means affording continuous restricted communication between said bore and chambers, a valve member in said bore having a center position where the ends of said bore are closed and having opposite end positions where one or the other of the ends of said bore opens into the adjacent of said chambers, pilot cylinders on the ends of said body, said valve member having end parts extending into said cylinders, spring means in said pilot cylinders acting on the said end parts for normally centering said valve member, and means for conveying fluid pressure to said pilot cylinders for moving said valve member into its end positions against the influence of said springs, there being adjustable abutment members in said cylinders for predetermining the end positions of said valve member, and said valve member having a tapered portion at each end that is disposed in the end of the bore when the valve member is in its adjacent end position.

7. In a hydraulic system; a reversible fluid motor, a pump, a servo-valve connected between the pump and motor for reversibly controlling fluid flow to the motor, and a restrictor valve serially between the motor and the servo-valve and comprising a normally open restricted channel and a normally closed channel by-passing said restricted channel, and means responsive to a predetermined pressure on either side of said motor for opening said normally closed channel.

8. In a hydraulic system; a reversible fluid motor having a pair of ports, a pump, a servo-valve connected between said pump and the two ports of said motor for reversibly controlling the supply of fluid to said motor, and a restrictor valve serially connected between said motor and said servo-valve, said restrictor valve comprising a restricted channel normally connecting said servo-valve with the motor and a second channel by-passing said restricted channel, a valve member normally closing said second channel, and means responsive to a predetermined fluid pressure at either of the ports of said motor for moving said valve member into position to open said second channel.

9. In a hydraulic system; a reversible fluid motor having a pair of ports, a source of fluid pressure, a servo-valve connected to said source of pressure and having a pair of service ports connected with the ports of said motor for reversibly controlling of the supply of fluid to said motor, and a restrictor valve serially connected

between said motor and said servo-valve comprising a restricted channel normally connecting the servo-valve with the motor and a second channel by-passing said restricted channel, a valve member normally closing said second channel, and means responsive to a predetermined pressure at either of the service ports of said servo-valve for moving said valve member into position to open said second channel.
